Mason, Remond, & Company.

UNITED STATES PATENT OFFICE.

ALFRED F. JONES, OF LEXINGTON, KENTUCKY.

IMPROVEMENT IN VACUUM APPARATUS FOR TREATING DISEASES.

Specification forming part of Letters Patent No. 44,198, dated September 13, 1864.

To all whom it may concern:

Be it known that I, ALFRED F. JONES, of Lexington, Fayette county, State of Kentucky, have invented a new and useful apparatus, which I term a "Restorator," to be used in the treatment of diseases; and I do hereby declare that the following is a full, clear, and exact description thereof, reference being had to the accompanying drawings, making a part of this specification, in which—

Figure 1 is a perspective view of my restorator complete and ready for use. Fig. 2 is a vertical longitudinal section of Fig. 1. Figs. 3 and 4 show the construction of the gage which is used for registering the amount of pressure.

Similar letters of reference indicate corresponding parts in the several figures.

The object of my invention is to produce a uniform circulation of the fluids in the human body, and thereby induce a normal action of the secretory organs of persons afflicted with disease by inclosing the body within an air-tight vessel and exhausting air from said vessel so as to produce an external pressure, which can be regulated according to the strength of the person thus treated, as will be hereinafter described.

To enable others skilled in the art to make and use my invention, I will describe its construction and operation.

In the accompanying drawings, A represents a box, which may be constructed of wood or metal, or of both of these materials combined, and of any desirable shape and size. For all ordinary purposes the box A may be made of sufficient size to contain an adult when seated in the position represented in Fig. 2. The box A is entered through an opening in its top, which opening is surrounded by a flange, a, projecting outward, and constructed with a bead on its upper edge, as shown in Fig. 2. This opening through the box is provided with a cover, which is adapted to fit within the flange a, and this cover is constructed of two parts, b b', united together by a sliding fastening, which consists merely of two tenons or tongues formed on the portion b, which enter corresponding holes made in the portion b'. When these two portions b b' are put together, there is an opening between them, which is lettered d in Fig. 2, and adapted for encircling the neck of the person

sitting in the box, so that all that portion of the body below the neck can be inclosed within the box A. The cover b b' is adjusted in place after the person is comfortably seated in the box A, and as this cover does not hermetically seal the opening through the box A, I employ a cape, e, which forms a part of a hood, e', that incloses the head of the patient, with the exception of the breathing organs, as shown clearly in Figs. 1 and 2. The cape e extends over the top of the flanged opening above described, and is drawn tightly around the flange a by means of a strong band, f, the ends of which are crossed after the parts are all adjusted in place and affixed to sliding plates g g, which are moved by means of screws h h, as shown in Fig. 1. By means of the band f and the straps i the box A can be rendered air-tight without any inconvenience to the person sitting in it. The bands i draw the hood e' tightly around or about the head, so that air will not enter through the face-opening in this hood, and the cushions j j serve to protect the ears from painful pressure by the head-bands. If desirable, a cape, e', may be interposed between the surface of the cover b b' and the cape e, as shown in the sectional view, Fig. 2. The capes and hood should be made of some material which is impervious to air, and for this purpose india-rubber will be found to answer.

Having thus described the mode of making the apparatus air-tight, I will proceed to describe the method of exhausting air from the box A, and of determining the external pressure upon the person sitting in said box.

B represents a common air-pump having a single barrel or cylinder, which is connected to the box A so as to communicate with the interior thereof. The air pump may be connected to the box A by a permanent fastening, or it may be so applied to this box that it can be removed therefrom at pleasure.

The drawing, Fig. 1 represents the exhausting or air pump applied permanently to one side of the box A; but I do not confine myself to such an arrangement, as various modes of exhausting the air from the box A may be adopted.

C represents a dial-plate, which is properly graduated on its face, and k is an index hand or pointer which points to the numerals indicated on the dial-plate, and which is suitably

attached to a stem, *l*, that carries a pulley, *m*. The pulley *m* is inclosed by the box *D*, which is affixed to one side of the box *A*, as shown in Figs. 1 and 4. Beneath the pulley *m*, and arranged at right angles to this pulley, is another pulley, *n*. From the pulley *m* depends a cord, *o*, carrying a weight, *p*. This cord passes over pulley *m* and under pulley *n*, and is attached to an elastic drum-head, *E*, which is drawn tightly over the flange *s*, which surrounds an opening, *F*, through the side of the box *A*. When the pump *B* is operated, the pressure of the external air will force the elastic head *E* inward, as indicated in red lines, Fig. 4, and thus cause the loaded cord *o* to rotate the pulley *m*, and thus move the index-hand according to the amount of depression of the head *E*. By means of this indicator the operator can readily read off on the dial-plate the amount of pressure upon the person thus treated. When the external pressure becomes too great, the stop-cock *G* is opened, and air allowed to enter the box *A*, until the person sitting in it feels comfortable.

My improved apparatus operates upon the human system as an alterative, there being two atmospheres of different densities applied to the body at the same time—that which surrounds the body is light, while that which is taken into the lungs is heavy, or of the natural density. The pressure which is taken off the body, by partially exhausting the air from the box or chest *A*, together with the common atmosphere, which is taken into the lungs, forces the blood to the extremities, thus breaking up congestions and equalizing the nervous forces. An artery, a vein, and a nerve are always associated and run side by

side, from the largest to the most minute vessels, and any derangement in one affects the other. So, when there is congestion or accumulation of the blood at one point, from inflammation or any other cause, the nerves will suffer also, and reflect their influence on the general system. If this congestion be broken up, and the nerves be restored to their normal condition, the cause will be removed and the patient will be relieved. The exhausted-air treatment operates on the nervous system by diffusing and equalizing the nervous forces, thus restoring a more healthful action to the capillary circulation, and stimulating the lymphatic absorbents to take up the morbid excretions.

In experimenting with my invention I have cured paralysis, neuralgia, rheumatism, semi-nal weakness, asthma, bronchitis, and dyspepsia. I have cured deafness where there was no organic derangement of the ear, and I have reason to believe that when properly and judiciously applied many other diseases may be cured by my improved treatment.

Having thus described my invention, what I claim as new, and desire to secure by Letters Patent, is—

An apparatus for the treatment of disease, consisting of a receptacle, *A*, which is capable of being made air-tight, an air-pump, *B*, and a registering apparatus or gage for determining the pressure of air upon the person partially inclosed within said receptacle, substantially as described.

ALFRED F. JONES.
